UNITED STATES PATENT OFFICE.

GEORGE W. STANTON AND RUFUS H. FRYE, OF ATHENS, TENNESSEE.

PORABLE LAMP.

1,191,744.

Specification of Letters Patent. Patented July 18, 1916.

Application filed July 20, 1915. Serial No. 40,928.

To all whom it may concern:

Be it known that we, GEORGE W. STANTON and RUFUS H. FRYE, citizens of the United States, residing at Athens, in the county of McMinn, State of Tennessee, have invented certain new and useful Improvements in Portable Lamps; and we do hereby declare the following to be a full, clear, and exact description of the invention, such as will enable others skilled in the art to which it appertains to make and use the same.

This invention relates to a portable lamp.

An object of the invention resides in the provision of a lamp which is of the electric type and may be used as a clock lighter, a desk lamp or a hand lamp.

A further object of the invention resides in so constructing the device that there will be no necessity for loosening wires or thumb screws when transferring from one use to the other.

With these and other objects in view, such as will appear as our description progresses, our invention comprises the combination and arrangement of parts as set forth in and falling within the scope of the appended claims.

In the drawings: Figure 1 is an elevational view of our device; Fig. 2 is a plan view; Fig. 3 is a plan view of the base; Fig. 4 is a section on line 4-4 of Fig. 2; Fig. 5 is a fragmental detail of the means for holding the lamp; and Fig. 6 is a fragmental detail of the circuit closing switch used when the device is used as a hand lamp.

Referring to the drawings by reference characters wherein like parts are indicated by like characters throughout the several views; in the embodiment of our invention shown in the drawing, a base 1 of suitable insulating material is provided. Secured to this base by means of a screw 2, is a metallic standard 3. This screw 2 extends upwardly beyond the horizontal portion of the standard 3 and is provided with a pair of nuts 4 and a thumb nut 5 for a purpose which will later appear.

Mounted on the upper end of the standard 3 is a spring clip which consists of a pair of plates 6 disposed to the sides of the said standard and secured together by a rivet 7 and a thumb screw 8 which screw is disposed at one end of the clip. Pivotally mounted between the plates 6 at the other end of the clip on a thumb screw 9 is an arm 10 which may be held in any ad-

justed position by means of the said thumb screw. A second rod 11 is adjustably mounted on the rod 10 by means of a spring clip 12, the action of which is controlled by a thumb screw 13. An extension 14 is adjustably mounted on the end of the arm 11 and may be secured rigidly thereto by a thumb screw 15. Mounted on this extension 14 is a plate 16 which is insulated therefrom and consequently from the standard 3. A reflector 17 is mounted on this plate and a lamp 18 extends through the plate and is located within the reflector. Secured to the extension 14 is a second plate 19 which contacts with the end of the lamp 18 and is in electrical communication with the extension 14 and the standard 3.

Mounted on the base 1 is a screw 20, on the upper end of which is round head. This screw has a plurality of nuts 21 mounted thereon for a purpose which will later appear. A dry cell 22 is mounted on the base 1 adjacent the standard 3 and a rod 23 extends upwardly from the base and thence horizontally and is connected to the standard. The battery is secured to the standard and to this rod by a wire 24. The horizontal portion of the standard forms a convenient handle by means of which the device may be carried. Secured between the nuts 4 on the screw 2 is a spring switch 25 which is adapted to be swung into engagement with the round head of the screw 20. Extending from the screw 20 and secured between the nuts 21 thereon is a wire 26 which is connected to one pole of the dry cell 22. A second wire 27 extends from this cell and is connected by means of a thumb screw 28 to the plate 16. Thus when the switch 25 is in contact with the screw 20 a circuit will be completed through the aforementioned wires and switch and through the standard 3.

In order that the circuit may be completed by a person remote from the lamp, so that the device may be used as a clock lighter, we have connected a wire 29 to each of the screws 2 and 20, which wires extend beneath the base 1 and are connected to contacts 30 which are secured to the base in the manner shown in Fig. 4 of the drawing. A base plate 31 is provided on which a pair of contacts 32 are mounted which have their ends turned upwardly at 33. Connected to these upwardly turned ends are wires 34 which have contacts 35 on their ends and leather operating handles 36. These contacts 35

are normally pressed apart by a coil spring 37. The base 1 may be placed upon the base plate 31 so that the contacts 30 on the former will engage the contacts 32 on the latter and thus when the contacts 35 are moved into engagement with each other the circuit through the lamp will be completed. A pair of blocks 38 are secured to the base plate 31 and are adapted to engage the edges 5 of the base 1 so that the latter will be readily positioned upon the base plate 31. It will thus be seen that when the base is placed upon the base plate that the lamp may be controlled from any portion of a room. 10 This is particularly useful as the device may be used for illuminating the face of a clock and the contacts 35 placed adjacent a bed for instance so that the clock may be lighted and the time observed by a person in the 15 bed.

It will be noted that the lamp together with its supporting means may be lifted bodily from the base plate and used as a hand lamp.

20 25 While we have illustrated and described a particular embodiment of our invention it has merely been for the sake of convenience and we do not wish to be limited to that particular embodiment as it is obvious 30 that numerous changes may be made within the scope of the appended claims.

What we claim is:

1. In a portable lamp, the combination

with a base having an open circuit thereon in which a lamp is included, the said circuit 35 including also a pair of spaced binding posts, a spring switch pivotally mounted on one of said binding posts and adapted to engage the other, a pair of contacts mounted on the under face of said base, wires extending from said binding posts to said contacts, a base plate having contacts thereon adapted to engage the first mentioned contact and wires having a switch thereon connected to the contacts on the base plate. 40 45

2. In a portable lamp, the combination with a base of a standard mounted thereon, a telescopic arm adjustably mounted on the standard, an extension adjustably mounted on the arm, a plate secured to the extension and insulated therefrom, a second plate mounted on the extension, a lamp secured to the first mentioned plate and contacting with the second mentioned plate, the said plates being included in an electrical circuit and manually controlled means for closing said circuit. 50 55

In testimony whereof, we affix our signatures, in the presence of two witnesses.

GEORGE W. STANTON.

RUFUS H. ^{his} FRYE.
